UNITED STATES PATENT OFFICE

2,591,152

SWITCH ACTUATOR FOR MODEL RAILROADS

Oscar C. Hewett, Fort Worth, Tex.

Application April 29, 1946, Serial No. 665,691

1 Claim. (Cl. 246—231)

1

This invention relates to electrical actuating devices, and has particular reference to an actuator which may be adapted for use in model railroads.

One object of the invention is to provide an efficient switch actuator which has its operating parts mounted beneath the table on which the model railroad is set up, thus lending realism to the miniature arrangement.

Another object of the invention is to provide an actuator which will lock the movable switch points of a model railroad in either position, or will actuate other devices such as switch stands and the like, yet one which is easily operated and with relatively little electrical energy.

A further object of the invention is to provide an electrical actuator of the solenoid type which includes a mechanical advantage between the point of application of power and the point of delivery, such as at the tiebar of a railroad switch.

A further object of the invention is to provide, in addition to the locking feature referred to, a movement of the solenoid armature before switch operation so as to gain the advantage of kinetic energy thus created.

These and other objects of the invention will become apparent from the following description of the accompanying drawings, wherein:

Figure 1 is a perspective view of the new actuator.

Figure 2 is a broken perspective view of the central portion of the actuator armature, the vertical shaft, and the lever arm co-acting therebetween.

Figure 3 is a plan view of the mechanism shown in Figure 2, and illustrates the various operating positions in dotted lines.

Figure 4 is a plan view of a miniature railroad switch, and showing the connection between the upper lever and shaft of the present invention with the tiebar of the switch.

Accordingly, the new actuator includes a square tube 1 of non-ferrous or other material not affected by magnetic lines of force, such as brass, and in which there is slidably positioned an armature 2 of ferrous or other magnetizable material, which armature is square or rectangular in cross section. A mounting bracket 3 in the form of an inverted U, and of non-magnetic sheet material encloses the central portion of the tube 1 in the manner shown in Figure 1.

Wound around the extending ends of the tube 1 there are solenoids 4 and 5 and connected as shown in the drawings. Each solenoid 4 and 5 includes containers 6 and 7 at each end and

2

which containers 6 and 7 are mounted around and retained by the ends of the tube 1.

Referring now to Figures 2 and 3, the central upper face of the armature 2 is provided with a V-shaped groove 8, and which groove includes laterally extending portions at the outer ends thereof to form shoulders 9. The described groove arrangement includes a projecting triangular portion 10 between the sides of the V, and which portion is an important part of the invention, as will be seen in the description of operation.

Extending upwardly from the upper surface of the central bracket 3, and to the side of the longitudinal center of the tube 1, there is a collar 11 which is secured to the said bracket and having thereabove a freely rotatable flange collar 12, both of which collars rotatably receive a vertical shaft 13. The flange collar 12 is provided with holes 14 for screwing the flange of the said collar to the upper surface of a table (not shown). Similarly, the bracket 3 is provided with other holes 15 for securing the same to the under surface of the table.

The lower end of the shaft 13 is provided with a rigidly secured lever or arm 16 having a downwardly projecting pin 17 at its outer end, and which pin is engaged by the previously referred to groove 8 in the armature 2. Although not shown in the drawings, the tube 1 is opened at this point to accommodate the arm 16.

At the upper end of the shaft 13 there is another arm 18 having a set screw 19 in its side for engaging the said shaft. By this arrangement the relative angular position may be varied to adjust the throw of the model railroad switch, to be described. Also, the upper arm 18 is provided with a multiple of holes 18a at various distances from the shaft 13 so as to adjust the leverage of the throw.

Referring now to Figure 4, wherein a switch for a model railroad is shown to illustrate an application of the present actuator, the end of the shaft 13 is shown and the upper arm 18 is illustrated in its operating position. It will not be necessary to describe all of the switch in detail, be it sufficient to say that the same includes branched parallel tracks 20, and hinged movable switch points 21 of conventional construction positioned therebetween. The switch points 21 are moved in unison by a tiebar 22 connected thereto, and which tiebar is connected by a link 23 to the upper arm 18.

Referring now to Figure 2, a helical compression spring 24 is shown mounted around the lower end of the vertical shaft 13 and above

the lower arm 16, and which spring bears against the bracket 3 and the said arm. The spring is not an important element of the invention, but tends to retain the lower arm pin 17 within the groove 8, and to retard the action of the arm 16.

In operation, the armature is connected with the switch tiebar 22 as shown in Figure 4 and mounted to the table (not shown) as previously referred to. As particularly shown in Figure 3, the position of the lower pin 17 against the shoulder 9 of the groove 8 locks the shaft 13 against torque applied to the latter. Upon energizing the solenoids 4 and 5, the armature 2 is caused to move to one of its extreme positions. In so doing the armature 2 moves approximately the width of the groove 8, whereafter the triangular projection 10 strikes the said pin, and by reason of its angular position, moves the pin 17 along one side of the groove 8. After reaching the center of the V, the other side of the groove 8 engages the pin 17, and carries the same to the groove of the shoulder 9, thus locking the arm 16 in its other thrown position. To reverse the position of the actuator, the armature is merely moved in the opposite direction by reversing the direction of flow in the solenoids 4 and 5, whereupon similar but converse actions take place between the lower arm pin 17 and the V groove 8.

What I claim is:

An actuator for a model railroad switch to be

mounted on the surface of a table, said actuator comprising a mounting bracket adapted to be secured to the lower surface of said table, a solenoid supported by said bracket, a flat bar armature forming a part of said solenoid and slidably mounted therein, a V-shaped groove in said armature, said groove including laterally extending portions at the outer ends thereof, a vertical shaft extending upwardly above said armature and adapted to extend upwardly above the upper surfaces of said table, bearing means rotatably supporting said shaft, an arm secured to the lower end of said shaft and engaged by said groove, and an upper arm mounted on said shaft above said table top adapted to be operatively connected with said model railroad switch.
